UNITED STATES PATENT OFFICE.

AUGUST HANKE, OF JERSEY CITY, NEW JERSEY.

BOTTLE-LABELING MACHINE.

No. 834,126.

Specification of Letters Patent.

Patented Oct. 23, 1906.

Application filed November 19, 1904. Serial No. 233,494.

To all whom it may concern:

Be it known that I, AUGUST HANKE, a citizen of the United States, and a resident of Jersey City, in the county of Hudson and 5 State of New Jersey, have invented a new and Improved Bottle-Labeling Machine, of which the following is a full, clear, and exact description.

The invention relates to label-affixers; and 10 its object is to provide a new and improved labeling-machine more especially designed for conveniently and quickly applying labels to bottles while filling and corking the same, the label-affixer being actuated by and in 15 unison with the filling and corking devices.

The invention consists of novel features and parts and combinations of the same, as will be more fully described hereinafter and then pointed out in the claims.

20 A practical embodiment of the invention is represented in the accompanying drawings, forming a part of this specification, in which similar characters of reference indicate corresponding parts in all the views.

25 Figure 1 is a sectional side elevation of the improvement. Fig. 2 is an enlarged plan view of the same. Fig. 3 is an enlarged sectional front view of the label-feed. Fig. 4 is a transverse section of the same on the line 4 30 4 of Fig. 3. Fig. 5 is a sectional side elevation of a modified form of the improvement, and Fig. 6 is a transverse section of the same on the line 6 6 of Fig. 5.

On a suitably-constructed frame or work-bench A is held a dish-like receptacle or support B for supporting the bottle C to be filled, corked, and labeled while in an upright position in the said receptacle B. The bottle while in this position is engaged at its 40 neck by a clamping or holding device D, controlled by a treadle D' and provided with a valved supply-pipe E for filling the bottle with soda-water or other liquid. After the bottle is filled and the supply shut off then 45 the bottle is corked by a corking device F, actuated by a weighted lever F' under the control of the operator in charge, said corking device F being connected to a cross-bar F², which is connected by rods F² to a frame 50 F⁴, which in turn is connected to the lever by links G⁴. The label-affixer, presently to be described in detail, is actuated from the treadle D' and the lever F', so that the label is affixed while the bottle is being filled and 55 corked in the usual manner. For the purpose described the following arrangement is

made: A carriage G, on which is journaled a roller H for applying an adhesive substance to the reverse face of the label I, is mounted to travel upon guideways A', arranged on the work-bench A, the carriage being provided with rollers H⁴, traveling upon the guideways, the rear rollers H⁴ being journaled upon the extended ends of the shaft bearing the roller H, Fig. 2. By this construction the roller H is positively rotated, so that every part of the periphery thereof receives paste from the rollers K³. The labels which are to be successively picked up by the roller H are arranged in a pile resting on a plunger J, mounted to slide vertically in a label-box J', set on the work-bench A. The roller H normally in a rearmost position travels over the uppermost label when the carriage G is moved forward, and as the peripheral face of the said roller is provided with an adhesive substance the latter is transferred onto the reverse face of the label. During the forward travel of the carriage G the roller moves in contact successively with the tops of a number of paste-supply rollers K in contact at their lower portions with an adhesive substance, such as paste, contained in a paste-box K', held on the work-bench A adjacent to the label-box J'. The 85 label carried forward on the peripheral face of the rotating roller H finally passes onto a fly L, which delivers the pasted label to a swing-rack N, adapted to apply the label to the side of the bottle C, as hereinafter more 90 fully described.

The carriage G, previously mentioned, is moved forward when the operator presses the treadle D', and for this purpose the sides of the carriage G are connected with ropes G¹, extending over pulleys G² to connect with levers G³, fulcrumed on the work-bench and connected by links G⁴ with the treadle D', so that when the latter is pressed downward a forward traveling motion is given to the carriage G and its roller H. The rear end of the carriage G is connected with a rope G⁵, extending over a pulley G⁶ and carrying on its lower end a weight G⁷, so that when the operator releases the pressure on the treadle D' then the weighted rope G⁵ pulls the carriage G and its roller H back into a rearmost position.

The fly L is provided with a number of longitudinally-extending arms adapted to pass into annular recesses H', formed in the roll into annular recesses H', formed in the roller

H, so that when the carriage G and its roller H travel forward the free end of the fly passes under the non-gummed or face side of the label, and on the further rotation of the roller 5 the label completely passes onto the said fly. When this has been done, the fly L swings forward to deliver the pasted label onto the swing-rack N, and in order to give the desired motion to the said fly the following device is provided: The shaft L' of the fly is 10 pressed on by a spring L² to normally hold the fly in a rearmost position—that is, resting against the front end of the paste-box K', as illustrated in Fig. 1. On the shaft L' is 15 secured an arm L³, connected by a link L⁴ with a lever L⁵, connected by a link L⁶ with an upright lever L⁷, extending with its upper terminal into the path of the carriage G, so that when the latter is moved forward on the 20 operator pressing the treadle D' then the carriage imparts a swinging motion to the lever L⁷, whereby the fly L is actuated immediately after the label has passed onto the fly. Now when the fly is actuated it swings forward and downward against the tension of 25 the spring L² to deliver the label onto a cushion N', made of felt or other suitable material, arranged on the free end of the swing-rack N, the said cushion N' being approximately of the shape of the face of the bottle C 30 at the portion designed to receive the label, as will be readily understood by reference to the full and dotted lines in Fig. 1.

The swing-rack N is provided on its shaft 35 N² with an arm N³, pressed on by a spring N⁴ to normally hold the swing-rack N down on the work-bench A in a label-receiving position, and the said arm N³ is connected with a rope N⁵, extending over a pulley N⁶ and attached to the lever F' for operating the corking device F. When the corking-lever F' is 40 actuated, an upward and forward swinging motion is given to the swing-rack N, so that the cushion N' thereof carries the pasted label upward and firmly presses the same in 45 position on the bottle C—that is, at the time the corking-lever F' is pressed and the cork pushed home in the neck of the bottle.

It is understood that when the treadle D' 50 is released the carriage G moves back to its rearmost position, and in doing so it releases the lever L⁷ to allow the spring L² to return the fly L. When the operator releases the corking-lever F', the latter swings back to its 55 normal position by its weight and in doing so releases the pull on the swing-rack N to allow the spring N⁴ thereof to return the swing-rack to its normal or receiving position.

From the foregoing it will be seen that the 60 labeling-machine is controlled by the filling and corking machine, so that the bottle while being filled and corked receives the label.

In order to insure a proper upward feeding 65 of the pile of labels, so that the uppermost

label is always taken up by the roller H, the following device is provided: The plunger J for supporting the pile of labels is provided with a depending rack J², in mesh with a pinion J³, secured on a shaft O, extending in a 70 spring-casing O', containing a spring O², secured with one end to the said shaft O and at its other end to the casing O'. On the shaft O is secured a pinion O³, in mesh with a gear-wheel P, secured on a shaft P', carrying an escapement-wheel P², engaged by an escapement P³, carrying on its shaft P⁴ a curved arm P⁵, adapted to be engaged by the roller H when the carriage is moved forward or backward to impart a swinging motion to 80 the said arm P⁵ to actuate the escapement P³, and consequently allow an intermittent turning movement of the escapement-wheel P² by the action of the spring O², whereby the rack J² is caused to move upward, and with it the plunger J and the pile of labels I held on the said plunger.

It is understood that the gearing and escapement are so proportioned as to raise the plunger J a distance corresponding to the 90 thickness of a label for each operation of the machine to bring the uppermost label always in proper relation to the peripheral face of the roller H.

As shown in Fig. 2, the labels used are 95 segmental, and the fly L is provided with a segmental stop-bar L⁸ for the lower edge of the label to rest on to hold the label in proper position during its transfer from the roller H to the cushion N' of the swing-rack N.

In the modified form illustrated in Fig. 5 the roller H² passes over paste-supply rollers K² in contact with another set of rollers K³, immersed in the paste contained in the paste-box K⁴, which latter is now arranged in the 105 rear of the label-box J⁵, containing the labels I, resting on a plunger J⁴, vertically movable in the said box. In this case the roller H² when the carriage is moved forward on the operator pressing the treadle D' first takes up 110 the paste and then passes over the uppermost label to gum the same and to carry the label along onto a spring-pressed swing-arm Q, adapted to take the label off the roller and deliver it to a spring-arm R, supported on the 115 work-bench A. This arm R holds the label in position for the cushion N' of the swing-rack N⁷ to take hold of the label and carry the same to the bottle C on actuating the 120 corking-lever F', as previously explained. The arm Q is swung from its normal position (shown in Fig. 5) forwardly to the arm R by a projection Q⁵, held on the carriage G⁸ for the roller H². On the shaft H³ of the roller H are secured arms S, engaged by the ropes G' 125 for moving the carriage, and on each arm S is journaled a friction-roller S', adapted to travel over a guide-rail S², supported on the work-bench A. When a pull is exerted on the ropes G', then the arms S are swung into 130

an angular position previous to moving the carriage G^s forward, so that the roller H^2 can drop sufficiently downward to travel over and in contact with the supply-rollers K^2 and the uppermost label I , as previously explained. When the carriage is on the return travel and the pressure on the ropes G' is released, then the arms S return to a vertical position by the action of the weighted cord 5 G^5 , so that the friction-rollers S^7 travel up the inclined forward ends of the rails S^2 to lift the roller H^2 sufficiently to bring the under surface thereof above the uppermost label I and the rollers K^2 . The swinging 10 motion of each arm S is limited by stop-pins $S^3 S^4$. The guideway A^2 for the carriage G^s is provided with a spring-pressed top bearing A^3 to allow vertical movement of the carriage and its roller H^2 for the purpose above 15 explained. In order to feed the plunger J^4 intermittently, the following device is provided: From the plunger J^4 depends a rack J^6 , in mesh with a pinion J^7 , secured on a shaft O^4 , carrying a ratchet-wheel O^5 , engaged by a 20 pawl O^6 , fulcrumed on the lower end of a rod O^7 , pressed on by a spring O^8 and extending with its upper end in the path of the carriage G^s , so that when the latter is moved forward the rod O^7 is pressed downward against the 25 tension of its spring O^8 , and during the downward movement of the rod the pawl O^6 turns the ratchet-wheel O^5 , shaft O^4 , and pinion J^7 for the latter to impart an upward traveling motion to the rack J^6 , the plunger J^4 , and the pile 30 of labels resting on the said plunger. Thus by the arrangement described the labels I are fed intermittently upward to bring the labels in proper relation to the peripheral face of the roller H^2 for the latter to pick up a label on 35 its forward movement. It is understood that in either case the roller H^2 is caused to travel bodily forward and to rotate, so as to pick up paste and a label, thereby transferring the paste onto the face of the label and bringing the label into such position as to be 40 readily taken up by the fly L or arm Q , to be then transferred to the swing-rack N or N^3 and finally onto the bottle C .

Having thus described my invention, I 45 claim as new and desire to secure by Letters Patent—

1. The combination with a bottle-corking device, of a labeling-machine having a label-holder, a gumming-roller having a rotating

and a bodily-traveling motion, and adapted 55 to pass over a label to gum the same and carry it along, a transferring device for carrying the label from the gumming-roller to the bottle, means for operating the corking device, and means whereby the operation of 60 the corking device may operate the gumming roller and transferring device.

2. A labeling-machine comprising a label-holder, a paste-box for containing paste, supply-rollers extending into the paste, a 65 label-gumming roller adapted to pass over the supply-rollers, to take up paste and to pass over the reverse face of a label, to deliver paste to the same, means for taking the label off the said gumming-roller, and means 70 for applying the label to the bottle.

3. A labeling-machine comprising a label-holder, a paste-box for containing paste, supply-rollers extending into the paste, a 75 label-gumming roller adapted to pass over the supply-rollers, to take up paste and to pass over the reverse face of a label, to deliver paste to the same, a fly for taking the label off the said gumming-roller, and a swing-rack receiving the label from the fly 80 and carrying and applying it to the bottle.

4. A labeling-machine provided with a label-feed comprising a plunger for a pile of labels to rest thereon, a label-roller adapted to pass over the uppermost label of the pile, 85 a spring-controlled gearing for moving the said plunger, and an escapement controlled by the said roller and controlling the said gearing.

5. A labeling-machine comprising a label- 90 feed, a paste-box for containing paste and provided with paste-feed rollers, a carriage mounted to travel, a gumming-roller journaled in the carriage and adapted to travel over the uppermost label and the said paste- 95 feed rollers, a fly actuated from the said carriage and adapted to take the label off the said roller, and a swing-rack for receiving the label from the said fly and carrying it to and against the face of the bottle. 100

In testimony whereof I have signed my name to this specification in the presence of two subscribing witnesses.

AUGUST HANKE.
